(57) **CLAIM**

The ornamental design for a thumb guard with tap, as shown and described.

DESCRIPTION

FIG. 1 is an isometric view showing the exterior of one side and part of the interior of the other side of the thumb guard with tap;

FIG. 2 is an isometric view showing the top and the exterior of one side of the thumb guard with tap;

FIG. 3 is a top plan view thereof;

FIG. 4 is a side elevational view thereof, the other side being the mirror image;

FIG. 5 is a bottom plan view thereof;

FIG. 6 is a rear elevational view thereof;

FIG. 7 is a front elevational view thereof; and,

FIG. 8 is a cross-sectional view showing the interior of one side of the thumb guard with tap.

The hand in FIG. 1, the hands, the hand-held device, the additional thumb guard in FIG. 2, and the padding in FIG. 8 are shown in dot-and-dash broken lines as they are environmental structures intended to illustrate the claimed design in use. None of the broken-line subject matter forms a part of the claimed design.
